UNITED STATES PATENT OFFICE.

MALCOLM F. GASCON, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,395,991.

Specification of Letters Patent.

Patented Nov. 1, 1921.

Application filed February 7, 1919. Serial No. 275,538.

To all whom it may concern:

Be it known that I, MALCOLM F. GASCON, a citizen of the United States, residing at Detroit, in the county of Wayne and State 5 of Michigan, have invented certain new and useful Improvements in Adding-Machines, of which the following is a specification.

My present invention relates to the printing department of an adding machine and 10 the object is to provide for automatic control by the laterally shiftable paper carriage in the matter of elimination of imprints. Machines of the character with which this invention is concerned are equipped to do 15 tabulating work as for example in the making of book entries upon loose leaf ledgers, and such work frequently requires subdivision of the printing mechanism, as for the printing of date, folio number and amount, 20 and the work in hand may require that printing be omitted with the carriage in one or another of its columnar positions, that is to say printing by one or more or all of the subdivisions of the printing mechanism. 25 In recent developments of machines of the kind here concerned as high degree of automaticity as may be practicable is sought and this involves avoidance of repetition in fingering for setting up of matter which 30 may require printing more than once in the same tabulation. At the same time not all of the matter so set up and maybe not any of it should be printed at a certain position or at certain positions in which the paper 35 carriage may stand as the tabulation proceeds.

By my present invention I make provision for the exercise of a control, through the agency of fixtures upon the paper carriage, over impression-making devices, such 40 as the familiar spring-driven hammers belonging to different subdivisions of the printing department of the machine.

In the drawings which accompany and 45 form part of this specification Figure 1 represents a sectionalized left side elevation of a machine of the familiar Burroughs type, with parts not necessary for a complete disclosure of the invention, omitted, the portion 50 at the rear below the paper carriage being taken on the section line 1-1 of Fig. 2; Fig. 2 is a horizontal section taken substantially on the line 2-2 of Fig. 1; Fig. 55 3 is a rear elevation showing the lower portion of the paper carriage and certain asso-

ciated parts; Fig. 4 is a sectional elevation of some of the parts appearing in Fig. 1 but at an advanced stage in an operation of the machine; Fig. 5 is a perspective view of certain elements of the carriage-controlled mechanism; Fig. 6 shows other elements thereof in perspective; Fig. 7 is a detail sectional view taken on the line 7-7 of Fig. 2, and Fig. 8 shows an example of work.

The machine proper requires no description, being thoroughly familiar to those skilled in this art, and this applies also to the general characteristics of the paper carriage. It may be well to further state that 70 in the prior application of one Robert L. Muller, Serial No. 268,064, filed December 23, 1918, there is disclosed a machine with carriage-controlled mechanism inclusive of that now made the subject of the present 75 application, and the example of work supplied by Fig. 8 is the same, as far as it goes, as that shown by Fig. 5 of said Muller application. In view of the relationship of the disclosures of this and said Muller application, I shall use reference characters 80 corresponding with those of the latter to designate corresponding parts.

There is the usual tabulation rod 9 journaled in the side pieces 8^a of the paper carriage and carrying stop fingers or dogs 12 to coöperate with the fixed stop 13 on the back panel of the machine casing. Then, as in the Muller application, there is another and non-rotary rod 10 mounted in 90 said carriage side-pieces somewhat above and rearward of the tabulator rod 9, and this rod 10 carries adjustable collars 14. These collars support rollers 72, 80, 41 and 75 of varying diameters. While these rollers correspond in function with those similarly designated in the Muller application, it should be noted that the present disclosure does not duplicate that of said application 95 in the matter of multiplicity of rollers in different sets and their adjustability, which is characteristic of the Muller invention. So far as the present invention is concerned it is sufficient to consider only a single roller at each location along the rod 10. These 100 rollers are all designed to ride upon the cam-like end of a lever arm 7, with varying effects governed by differing diameters of the rollers, the greater the diameter of the roller the greater the degree of depression 110

of the said lever arm. The degree of depression of this arm determines the extent to which the printing mechanism of the machine will be disabled. The printing department of the machine, as here shown, particularly in Fig. 2, is subdivided into three sections, one of which may be considered as devoted to the printing of dates, another to the printing of folio numbers, and 5 the third to the printing of amounts. Under the particular arrangement here shown, and having reference to the example of work supplied by Fig. 8, depression of the lever arm 7 to the least extent, as by the smallest 10 roller 72, results in the disabling of only the middle section of the printing devices, to wit, those allotted to folio printing, whereas depression of said lever arm to the greatest extent, as by roller 30, results in 15 disabling all three sections of the printing mechanism. Depression of said lever arm to the medium extent, as by either the roller 41 or the roller 75, results in disabling the date and folio sections of the printing 20 mechanism.

The printing mechanism proper is that long familiar in Burroughs adding machines, comprising a gang of hammers 715 and hammer driving levers 716 and latches 25 717 which normally restrain the hammers. The splitting or sub-dividing is done in the usual way by omitting overlapping tails between latches, and in the present instance the split is a permanent one. However, certain 30 devices of the same character as the couplings shown in the Vincent Patent 1,166,096 of December 28, 1915, are employed for purposes of the so-called "hammer blocking." There is not actual blocking 35 of hammers, as in the construction of the said patent, but the principle of imprint-elimination set out in the Gooch Patent 925,805 of June 22, 1909, is followed, *i. e.* printing is prevented by early release of 40 hammers so that they are deprived of percussive function.

I have before pointed out that the printing mechanism of the machine is sub-divided into as many as three sections. Then 45 the first or date section of the printing mechanism is itself sub-divided, in so far as concerns co-operative tripping action between the first and second latches, inasmuch as there should of course be no cipher printed between a month abbreviation and a day date when the latter has but a single numeral. Therefore the first latch 717 which controls the hammer for printing the month abbreviation does not have a tail 50 over-lapping the next adjacent latch which controls the hammer for printing a tens numeral of a day date. However, for purposes of "hammer blocking" these two latches are provided with coupling devices so that 55 a preliminary tripping of the middle one of

the three latches of this section of the printing mechanism will be accompanied by a tripping of the other two, it being observed that the middle latch has a tail over-lapping the third latch, as shown in Fig. 2. There 70 is applied to this middle latch a pitman 717^a, and there is a catch 717^b pivoted upon this pitman, said catch being normally upheld by a spring 717^c. In the present instance the catch has a lateral stud 717^d 75 (Fig. 7) which, when the catch is depressed, will take a position in front of the laterally turned end of a pitman 717^e that is pivotally connected at its forward end to the first latch 717. This condition is illustrated 80 in Fig. 4.

The catch 717^b has a shoulder *a* (Fig. 4) on its underside which is normally above the path of movement of the cross bar 160 of a bail which is vibrated in every operation of the machine. When the catch is depressed (through connections presently to be described extending from the "hammer block" lever arm 7) the said shoulder is brought into the path of said cross-bar, so 90 that at the outset of the operation of the machine the pitman 717^a will be drawn rearward and with it the pitman 717^e and so the three latches of this section of the printing mechanism will be tripped and their 95 hammers released and thereby deprived of percussive function,—the third latch being tripped by the tail of the second or middle latch.

The second section of the printing mechanism has five sets of printing devices which, of course, means that there are here five hammers to be controlled. The latch controlling the first of these hammers has a pitman 717^f similar in all respects to that which 100 is applied to the middle latch of the first-described section, and likewise a catch 717^g of the same sort, and furthermore this catch is adapted, when depressed, to be operated upon by the same bail cross-bar already described. The effect will be, of course, to trip all of the latches of the second section of the printing mechanism and deprive their hammers of percussive function so that 105 printing is prevented. The remaining, or amount printing section of the printing mechanism, similarly has a pitman 717^h and catch 717ⁱ connected with the latch controlling the first of its hammers, and its catch, too, is adapted, when depressed, to be operated upon by said bail cross bar. These three catches above referred to, may be selectively or collectively depressed, so that the middle section of the printing mechanism may be alone disabled, or the date printing 115 section may be disabled along with it, or all three sections of the printing mechanism may be simultaneously disabled.

The variable depression or setting of catches is done through the turning of a rod 120

130

170 journaled in the side pieces of the frame of the printing department. Thus said shaft carries lugs for depressing the catches, there being three such lugs 170^a (Fig. 6)

5 longitudinally alined for simultaneous action upon the three catches, and two such lugs 170^b for simultaneous action upon the catches of the date printing and folio printing sections of the printing mechanism, and a single 10 lug 170^c for depressing the catch of the latter section alone.

It will be recalled that the "hammer block" lever arm 7 is lowered varying degrees according to the size or diameter of the carriage roller riding upon it, and it is now 15 in order to state that this lever arm is coordinated with said rotary rod 170 through appropriate connections so that upon the degree of depression of the lever arm will depend the extent of disabling of sections of 20 the printing mechanism. Said arm is spaced considerably from the back panel of the machine casing so as to aline with the rollers, and it is formed as a side piece of a yoke 7^a 25 running below a long supporting stud 3 secured to said panel (Figs. 1 and 2). An enlarged portion fits against the latter and a reduced portion of said stud extends through it (with a flattened side to prevent 30 its turning) and a further reduced portion is screw-threaded to receive a clamping nut 3^a. A collar 3^b intervenes and an inner arm 7^b of the yoke journals on this collar. The outer yoke-arm 7 journals on a shoul- 35 dered screw 3^c tapped into outer end of the stud.

Said arm 7^b is bent into close proximity to the back panel and has its end notched to embrace the short rearwardly projecting arm 40 of a bell crank lever 178 pivoted at 179 and carrying upon its upstanding longer arm a supplementary arm 181 pivoted intermediate its length at the point 180, said supplementary arm 181 being spring-connected below 45 its pivot to the long arm of the bell crank lever 178 and being notched at its extremity above the pivot to embrace a stud on the rear end of a slide bar 182. The latter has a rack 182^a on its upper edge at 50 its front portion in mesh with a small gear or pinion 170^d on the rod 170.

The hub of the gear journals in one side plate of the printer frame, as shown in Fig. 2, and has prongs 170^e (Fig. 6) engaging a 55 slot in the enlarged end of rod 170. A screw 170^f secures the parts, being run through the gear and tapped into the rod. The other end of the latter receives a screw 170^g which is shouldered and supplies a trunnion journaled in the plate at this side of the printer frame.

It will be obvious that through above described connections depression of the "hammer block" lever arm more or less will result 60 in sliding the bar 182 rearward and

turning the rod 170 to a greater or less extent. (The compound make-up of the operating bell crank lever, with the yielding form of connection between its elements, is merely for safety purposes in case of a lock-up.) 70

A spring 191 is applied to the bar to normally hold it forward, and to consequently elevate the lever-arm 7, such normal condition constraining the rod to occupy the idle position, shown in Fig. 7, where none of 75 its projections 170^a, 170^b or 170^c is in action. Rearward shifting of the rack bar, as brought about by depression of the lever-arm 7 by the smallest roller 72, would cause the single projection 170^c to depress the catch 80 717^e, with the result of disabling only the middle section of hammers. Depression of the lever-arm by a middle-sized roller (41 or 75) would bring the two projections 170^b into action to additionally depress the catch 85 717^b, as shown in Fig. 4, and so result in disabling both the first (date) and second (folio number) sections of the printing mechanism. Depression of said lever-arm to the maximum extent (by the largest roller 90 30) would bring the projections 170^a into action, depressing all three catches 717^c, 717^d and 717^e, with the result of disabling all the printing hammers.

The slide bar 182 is suitably slotted to embrace supporting and guiding roller studs on the frame-work, the same being designated 192. In the under-side of this slide bar there are formed four notches 182^b, which define the different positions of the 100 slide bar and serve, in conjunction with a locking pawl, to insure its proper positioning and its being held positioned during an operation of the machine. The locking pawl is in the form of a slide plate 195 mounted 105 against one of the side plates of the printer frame and V-shaped at its upper end for engagement with one or another of the notches. A spring 196 applied to this slide plate tends to draw it upward into engagement with the notched slide bar. Normally this locking pawl is restrained by a stud 197^a carried by a bell crank 197 which constitutes one element of a train of mechanism for vibrating the bail whose cross-bar 110 160 operates upon any depressed catches. In the standard construction of the Burroughs machines there is a plate 801 fastened to a drive shaft 800 and a link 802 which operates a restoring bail 712 for the hammer driving levers 716 and their hammers. These are regular parts which reciprocate or vibrate in every operation of the machine and I find them convenient for functioning to operate the bail of which the cross-bar 115 160 constitutes a part. Thus I mount a roller stud 802^a on the link 802 and I form an angular end of the long arm of the bell crank 197 with an open cam slot embracing said roller stud. The shorter and upwardly 120 165 130

extending arm of said bell crank (Fig. 1) together with a link 197^b forms a toggle which is adapted to operate upon a lever 198 connected by a link 199 with one side 5 piece 160^a of the bail of which said cross-bar 160 is a part.

At the outset of an operation of the machine the roller stud 802^a elevates the long arm of the bell crank lever 197, straightening the before-mentioned toggle, rocking the lever 198, and lowering the link 199 so that the bail 160—160^a is swung forward, and will therefore trip any latches whose catches have been depressed into the path 10 of movement of the bail cross-bar 160 (Fig. 4). It will be noted also that the elevating of the long arm of said bell crank raises the stud 197^a so as to release the locking pawl 195 and permit it to engage the registering notch 182^b of the bar 182.

Referring now to the example of work represented by Fig. 8, and assuming that a ledger sheet A is inserted in the paper carriage of the machine, and that alongside of 15 it to the left there is inserted a customer's statement sheet B, the paper carriage will be first moved by hand to its extreme left hand position wherein the roller 75 may function to prevent any date or folio printing. With the carriage in this position, the customer's old balance is set up and the machine operated once to print and register that amount. In the example here given it appears first as \$500 and is printed on 20 the top line of the ledger sheet at the extreme right. The registering mechanism of the machine is, of course, in adding condition at this time. The paper carriage is then moved by hand to its extreme right hand position wherein the left hand or charge section if the customer's statement sheet is in position to be printed upon. In 25 this position of the carriage the roller 72 stands over the lever arm 7. The date, folio 30 number, and amount to be charged, are set up on the keyboard and the handle operated whereupon the machine goes through a cycle of operations, and as the lever arm 7 is depressed to the least extent, the date and amount will be printed but the folio number 35 will not be printed (such entry has no place on the customer's statement). The paper carriage is released at the end of the operation (through familiar tabulating action) and moves over to the next columnar 40 position in which the right hand section of the customer's statement stands opposite the printing type. In this new position the large diameter roller 30 depresses the lever- 45 arm 7 to the maximum extent in consequence of which the entire printing mechanism is disabled so that there will be no printing upon the customer's statement (it will be understood that this right hand section of 50 the customer's statement is for entries of

credit items only). With the conclusion of this operation of the machine, the carriage is again released and shifts to the next columnar position wherein the first column of the ledger sheet will be opposite the printing type. No "hammer block" roller comes into action here, so that date, folio number, and amount are all printed on the ledger sheet. After this operation of the machine, the carriage tabulates to the next column 75 of the ledger sheet which is used for the entry of credit items only, so that there should be a blank in this column. However, it is customary in business establishments 80 where machines of this character are employed to use a tally roll for collecting all amount entries in a condensed list for book-keeping purposes. Therefore when the carriage has shifted to this particular columnar position, the "hammer block" lever arm is 85 depressed by a middle sized roller in consequence of which the date and folio number will not be printed upon the tally roll, but only the amount. Of course there will be no printing upon the ledger sheet because of the interposition of the tally roll. 90

More charge entries may follow, the carriage being moved back to the right, and after that credit entries may be made, the new balance having meantime first been 95 printed in the third column on the ledger sheet, and then printed in the last or "Old balance" column preliminary to the entry of credit items. However, it is unnecessary to follow through in detail the more elaborate example, such as that used in the Muller application. It will of course be understood that various arrangements of rollers may be used to suit varying kinds of work. It is further to be understood that considerable 100 mechanical variations may be practised in carrying out the present invention. 105

I claim:

1. In a machine of the class described, the combination of printing mechanism subdivided for multi-column work, a laterally shiftable paper carriage, means for separately preventing printing operations in the different subdivisions of the printing mechanism, and means variably set by the paper 110 carriage, in its different column positions to determine the extent of imprint-elimination according to said subdivisions. 115

2. The claim 1 combination, the printing mechanism comprising spring-actuated hammers, retracting means and restraining devices, together with connections for tripping certain of said devices, and means controlled by the paper carriage for bringing said connections into action to cause early release 120 of hammers and thereby deprive them of percussive effect. 125

3. The claim 2 combination, the connections having settable catches, and the controlling means comprising a rotatable rod 130

formed to variably act upon said catches, together with a reciprocating element to engage the set catches.

4. The claim 3 combination, the catches being upheld by springs, and the rod having circumferentially spaced projections graduated in number.

5. The claim 3 combination, the rod having a gear, and the carriage-controlled means comprising a rack in mesh therewith, and a lever-arm operatively connected with said rack and variably actuated by the carriage fixtures.

6. The claim 1 combination, the carriage having laterally spaced rollers of varying diameters and the control-means including a lever-arm upon which said rollers ride.

7. The claim 5 combination, together with a locking pawl to hold the rack and rod at different settings.

8. The claim 7 combination together with a reciprocating machine element and a member initially actuated thereby to release the locking pawl, the latter being spring-drawn into engagement with the bar.

25

9. In a machine of the class described the combination of hammers, latches, pitmen connected to certain latches and having catches, a bail to act on said catches, a rotary rod with projections for setting the catches, a rack to rotate the rod, a pawl to lock the rack, a reciprocating machine element, a system of levers and links connected therewith and with the said bail and one member of which operates upon said pawl, a laterally shiftable carriage, and means controlled thereby for setting the rack bar.
